UNITED STATES PATENT OFFICE.

BEN RUBENSTEIN, OF NEW YORK, N. Y., ASSIGNOR TO RUBY LAMP MFG. CO. INC., OF NEW YORK, N. Y., A CORPORATION OF NEW YORK.

DESIGN FOR A LAMP STAND OR ARTICLE OF SIMILAR NATURE.

Application filed August 15, 1925. Serial No. 14,433. Term of patent 3½ years.

To all whom it may concern:

Be it known that I, BEN RUBENSTEIN, a citizen of Russia, residing at New York city, in the county of Kings and State of New York, have invented a new, original, and ornamental Design for a Lamp Stand or Article of Similar Nature, of which the following is a specification, reference being had to the accompanying drawing, forming a part thereof.

Fig. 1 is an elevational view of a lamp stand showing my new design.

Fig. 2 is a view showing detail of the front half of the symmetrical base thereof as employed in the complete design as shown in Fig. 1.

I claim:

The ornamental design for a lamp stand or article of similar nature, as shown.

BEN RUBENSTEIN.
